UNITED STATES PATENT OFFICE.

FRANK J. KROMENAKER, OF CHICAGO, ILLINOIS.

DESIGN FOR DICE.

59,970.

Specification for Design.

Patented Dec. 13, 1921.

Application filed June 27, 1921. Serial No. 480,943. Term of patent 14 years.

To all whom it may concern:

Be it known that I, FRANK J. KROMENAKER, a citizen of the United States, residing at Chicago, in the county of Cook and State of Illinois, have invented a new, original, and ornamental Design for Dice, of which the following is a specification, reference being had to the accompanying drawing, forming part thereof.

Figure 1 is a plan view looking toward one of the triangular faces of the dice;

Fig. 2 is a side elevation thereof;

Fig. 3 is a plan view looking toward one of the square faces of the dice; and

Fig. 4 is a side elevation thereof.

I claim:

The ornamental design for dice, as shown.

FRANK J. KROMENAKER.
